UNITED STATES PATENT OFFICE.

CHARLES G. PERKINS, OF HARTFORD, CONNECTICUT.

ELECTRIC-LAMP SWITCH.

SPECIFICATION forming part of Letters Patent No. 392,633, dated November 13, 1883.

Application filed July 24, 1883. Serial No. 280,924. (No model.)

To all whom it may concern:

Be it known that I, CHARLES G. PERKINS, a citizen of the United States, residing at Hartford, in the county of Hartford and State of Connecticut, have invented certain new and useful Improvements in Electric-Lamp Switches; and I do hereby declare the following to be a full, clear, and exact description of the invention, such as will enable others skilled in the art to which it appertains to make and use the same.

My invention relates to improvements in electric switches, more especially in switches for electrical incandescent lamps. The construction of my switch is such that breaking of the circuit is accomplished by a sudden movement. This feature my application has in common with others of its class.

My improvements reside especially in providing means for preventing sparking, such means consisting of a pair of spring-contacts supplemented by a third spring-contact. The operation of the switch is such that the first two springs make the initial contact and receive the sparks, while the third spring is pressed slowly into contact and makes good electrical connection.

My invention is illustrated in the accompanying drawings, in which—

Figure 1 is a plan of the lamp-circuit provided with my switch. Fig. 2 is a vertical section of the same on line xx in Fig. 1, and Fig. 3 shows a detail.

Referring to the drawings by letter, A is the base of the lamp-circuit, and B the casing thereof. Supported upon the base are insulated posts C and D, which form the socket-terminals and with which the terminals of the lamp co-operate in use. In line with each post is supported a set of springs, which are in the present instance of a triplicate construction, for a reason that will appear hereinafter. Going more into detail, there are three springs, E, F, and G, located near the post C, and three similar springs, H, I, and J, located near the post D. These springs are so arranged on being pressed toward the posts from behind that the two outer ones will first make contact and the inner one afterward. The springs are normally insulated from the posts. They constitute, however, the entering-terminals of the lamp-circuit. Accordingly, when they are

pressed into contact with their corresponding posts and when the lamp is in place, the circuit will be complete, and when they are out of contact with their posts the circuit will be broken.

As a means for operating the springs either to make or break the circuit, I employ devices attached to a shaft, K, which is supported in the casing of the socket and passes between the two sets of springs. The shaft K has a thumb-piece, L, by means of which it can be manipulated. The shaft is held in place by the ring k, which is pressed between the casing and the flange on the end of the shaft. Located centrally on the shaft is a sleeve, M, which is provided with a slot, m, through which the pin n on the shaft projects. The slot is large enough to allow considerable play to the pin. The sleeve M is provided with a squared head, and over this head and a part of the sleeve is pressed, while in the heated state, a piece of insulating material, O, such as glass or bunsilite. Any good insulating material will serve the purpose. I prefer to attach it to the sleeve while in the plastic state; but this is not necessary, as I may adopt other means of attachment.

It will be observed that the piece O is of a general elliptical shape, and that when its longest sides are presented to the springs they remain out of contact with the posts. If, however, the piece be turned a quarter-revolution the springs will be pressed against the posts and the circuit completed.

In practice, the turning of the insulating-piece O is accomplished by turning the shaft through the medium of the thumb-piece. The turning from the position shown in the drawings to a distance of one-quarter of a revolution is accomplished slowly, the two outer springs on either side of the log first making contact with their corresponding post and receiving the sparks, while the middle springs follow and complete the connection. In turning back, however, or in continuing to turn for another quarter of a revolution, the action will be somewhat different. Thus when the insulating-block has been carried until the springs press upon diagonally-opposite corners, then a slight movement beyond this point will put the block under the influence of the springs, which will thereupon throw it so as to break

contact quickly, and in that way overdo the effects of sparking.

The advantages arising from providing a supplemental contact-spring are apparent; but they are especially important in switches where the making of the contact is slow, while the breaking is sudden, as in the present construction.

It is of course not necessary that the initial contact should be made by two springs, as a single spring might receive the spark; but I prefer to employ two springs for this purpose, so as to minimize the effects of sparking.

Having now described my invention, what I claim is—

1. The combination, with a circuit-terminal, of a corresponding terminal made up of two

or more parts and an independent movable piece behind the parts, whereby the latter may be brought successively into contact with the first-named terminal, as and for the purpose set forth.

2. The combination, with a circuit-terminal, of a corresponding terminal made up of two or more springs and an independent movable piece behind the springs for moving the same successively into contact with the first-named terminal, as set forth.

In testimony whereof I have affixed my signature in presence of two witnesses.

CHARLES G. PERKINS.
